UNITED STATES PATENT OFFICE.

HERBERT CORRAL, OF PARKVIEW, HELENSBURGH, SCOTLAND, ASSIGNOR TO THE
SINGER MANUFACTURING COMPANY, A CORPORATION OF NEW JERSEY.

PANTOGRAPH EQUIPMENT FOR GROUPED EMBROIDERING-MACHINES.

1,328,821.

Specification of Letters Patent. Patented Jan. 27, 1920.

Application filed February 14, 1917. Serial No. 148,504.

To all whom it may concern:

Be it known that I, HERBERT CORRAL, a subject of the King of the United Kingdom of Great Britain and Ireland, and residing at Parkview, Helensburgh, Dumbartonshire, Scotland, have invented certain new and useful Improvements in Pantograph Equipment for Grouped Embroidering-Machines, of which the following is a specification, reference being had therein to the accompanying drawings.

The subject of this invention is a pantograph equipment for grouped embroidery machines as shown and described in the United States Patent to Herbert Corral and James M. Forbes, No. 1,159,901, dated November 9, 1915, for imparting simultaneously to a number of work-clamps movements similar to those traced by a pointer or the like manipulated by an operator.

An object of the invention is to provide a construction which permits of variation of the scale of reproduction with adjustment at a minimum number of points, the points of adjustment being all within convenient reach of the operator stationed at one end of the group of embroidery machines. Further objects and advantages will appear from the following description.

The improvement is illustrated in the accompanying drawing in which Figure 1 is a plan showing two of a series of work-clamps and Fig. 2 is a front elevation showing the frame or structure by which the work-clamps are carried. Figs. 3 and 4 are sectional elevations illustrating the means for vertically adjusting the work-clamps and the devices for suspending the supporting structure. Figs. 5, 6, 7 and 8 illustrate structural details.

Referring to the drawings, it will be seen that the work-clamps 1 are sustained by a rigid frame or structure adapted to perform translatory movements while remaining parallel to initial position and comprising the parallel bars 2 having adjustably clamped upon their opposite end portions the cross-members 2' respectively provided with a left hand extension 3 and a right hand extension 4. To the latter is pivoted at 5 one end of a link 6 connected at the opposite end 7 to one arm 8 of a bellcrank-lever or rocker which is mounted on a fixed fulcrum 9 and has its other arm 10 connected by the link 11 with one arm 12 of a second bellcrank-

lever or rocker which is mounted on a fixed fulcrum 13 and has its other arm 14 pivotally connected at 15 with a link 16 by which it is connected at 17 to the left hand extension 3 of the cross-member 2'. 60

The right hand extension 4 is formed at its free end with the member 18 inclined thereto which is undercut or otherwise adapted to form a guideway for a block 18' located at one corner of a parallelogram the sides of which are comprised by the members 19 and 20 jointed to said block by the stud 18'', and the members 21, 22, jointed at 23, the member 21 being also jointed to the member 19 at 24, and the member 22 70 being jointed to the member 20 at 25, an extension 22' of the member 22 being pivoted at the fixed point 26. Formed as an extension of the member 21 is an operating arm 21' carrying a pointer 29. 75

It will be seen that graduations are formed on the guide-member 18, and on the members forming the sides of the parallelogram, provision being made for adjustment of the connection of the sides at 24 and at 80 25, and for adjustment of the block in relation to the guideway.

The operation of the pantograph is effected in the usual manner, the movement of the pointer 29 being accompanied by deformation of the quadrilateral and displacement of the frame or structure carrying the work-clamps. 85

The bell crank-levers are mounted on suitable bearings and sustain the link 11 clear 90 of contact with the under side of the top of the bench or table sustaining the group of machines 6, while the supporting structure may be suspended from suitably chosen points by any usual or suitable means. 95

The work-clamps are maintained in light operative contact with the machine beds, each clamp having a rigid arm 27 hinged at 31 to one of the side bars 2 of the supporting structure and subject to the action 100 of a spring 32 tending to lift the arm, the screw 28 constituting a means of vertical adjustment for the work-clamp.

In lieu of the arrangement comprising the member 18 and block entering the guideway therein, any other suitable adjustable connection may be provided. 105

A circular wear-plate 33 is secured to the bench or table 6 by screws or otherwise upon which, during the operation of the panto- 110

graph, rolls the disk or wheel 34 journaled upon a screw-stud 35 tapped into an extension of the member 22.

- The supporting structure for the work-clamps is, in a preferred form of the invention, suspended from a member *c* of a suitable frame by cords *d* secured to one member of a clamp 30 embracing the frame-members 2 and thereby permits it to move freely above and closely adjacent to the bench or table, horizontally or parallel with the top of the bench or table. It will be observed that the bellcrank-levers or rockers 8, 10 and 12, 14, as well as the link 11 connecting the rockers, are mounted upon the table independently of the work-sustaining structure 2, and that the parallelogram, comprising the jointed sides 19, 20, 21 and 22, is also connected with the work-sustaining structure independently of the rockers. The parallelogram thus acts directly upon the work-sustaining structure and also indirectly thereon through the rockers 8, 10 and 12, 14 and their connecting link 11, in imparting and controlling the operative movements of the work-sustaining structure for all variations in amplitude of movement consequent upon adjustments of the parallelogram.
- Having thus set forth the nature of the invention, what I claim herein is:—
1. In a pantograph equipment for grouped embroidery machines, in combination, a laterally movable work-sustaining structure, a plurality of work-holders carried thereby, a plurality of rockers, a link connection between said rockers, independent link connections between said structure and said rockers, and a parallelogram directly connected with and adapted to impart operative work-shifting movements to said structure by means of its direct connection and its in-

direct connections through said rockers with the structure, said parallelogram having means affording the sole adjustment for varying the amplitude of work-shifting movements in all directions derived from controlling movements of said parallelogram.

2. In a pantograph equipment for grouped embroidery machines, in combination, a work-sustaining structure, work-clamps carried thereby, means for supporting said structure for horizontal movement, rockers sustained independently of said structure, links connecting the rockers each with said structure independently of said supporting means, a link connecting together said rockers, and a parallelogram having a single connection with said structure independent of the connections of the structure with said rockers and provided with adjusting means for producing variations in the amplitude of movement effective through said connection with the structure.

3. In a pantograph equipment for grouped embroidery machines, in combination, a work-sustaining structure supported for horizontal movement, work-holders carried thereby, and a single horizontally disposed parallelogram connected with and adapted to impart to said structure work-shifting movements in all directions, said parallelogram comprising means affording the sole adjustment for varying the amplitude of movement of the structure under control of the parallelogram.

In testimony whereof I have signed my name to this specification, in the presence of two subscribing witnesses.

HERBERT CORRALL.
